[57] CLAIM

The ornamental design for a film reel spacer, as shown and described.

DESCRIPTION

FIG. 1 is a front elevational view of a film reel spacer, showing my new design;

FIG. 2 is a top plan view thereof;

FIG. 3 is a right side elevational view, the left side being a mirror image thereof;

FIG. 4 is a front elevational view of a second embodiment thereof;

FIG. 5 is a top plan view thereof;

FIG. 6 is a right side elevational view, the left side being a mirror image thereof;

FIG. 7 is a fragmentary sectional view of the first embodiment, taken along line 7—7 of FIG. 1;

FIG. 8 is a fragmentary sectional view of the second embodiment, taken along line 8—8 of FIG. 4.

*Fig. 1.**Fig. 3.**Fig. 2.**Fig. 7.**Fig. 4.**Fig. 6.**Fig. 5.*
